Patented June 16, 1959

185,506

COIN CONTROLLED CIGAR VENDING MACHINE

Willie Allen Moore, Grambling, La.

Application June 30, 1958, Serial No. 51,590

Term of patent 14 years

(Cl. D52—3)

Fig. 1

Fig. 2

Fig. 1 is a perspective view of a coin controlled cigar vending machine, showing my new design.

Fig. 2 is a side elevational view of the machine shown in Fig. 1.

The rear of the machine is plain in appearance.

I claim:

The ornamental design for a coin controlled cigar vending machine, substantially as shown and described.
